UNITED STATES PATENT OFFICE.

HOSFORD D. KELLOGG, OF HAVERFORD, PENNSYLVANIA.

DESIGN FOR A RADIATOR.

Application filed July 20, 1922. Serial No. 3,139. Term of patent 3½ years.

To all whom it may concern:

Be it known that I, HOSFORD D. KELLOGG, a citizen of the United States, and a resident of Haverford, county of Delaware, and State of Pennsylvania, have invented a certain new, original, and ornamental Design for Radiators, as shown in the accompanying drawings, in which the figure is a perspective view of a radiator embodying the new design and as viewed from the front of the same.

I claim:

The ornamental design for a radiator substantially as shown.

In witness whereof, I have hereunto set my hand this 19th day of July, A. D. 1922.

HOSFORD D. KELLOGG.
